Garrettson Smith and Henry Brown, of Philadelphia, Penn.

assignors to

Raymond, Campbell & Company of Middletown, Penn.

Letters Patent No. 2105. Dated January 7, 1865.

Design for the plates of a stove.

The schedule referred to in these Letters Patent and making part of the same

Is as follows:

Be it known that we, G. Smith and H. Brown, of Philadelphia, County of Philadelphia, State of Pennsylvania, have invented, or produced a new and original design for the plates of the Susquehanna Cook Stove; and we do hereby declare the accompanying drawing with the following explanations of the same to form a full, clear and exact description of the said design.

In the drawing

Fig. 1 represents the front plate of the stove.

Fig. 2 a side plate.

Fig. 3 the back plate, and

Fig. 4 one of the feet.

R is the front plate, B one of the side plates, and C the back plate of the stove, and round the edges of each plate extends a beading a.

To the front plate are hung two doors D, above which is a register E, the latter sliding in an oblong panel enclosed by a plain beading B, and on the face of the panel below the register opening are the words "Susquehanna No. 7".

On the face of the plate A, near each side of the same is an ornamented foliated scroll F.

Round the doors D and also round the doors C and H, and panel I of the plate B extends a beading C, and in the centre of each door is a boss E, which is surrounded by a number of smaller bosses and by the ornamental figures

2
shown in the drawing.

DES. 2105

The back plate C is divided into three panels by vertical ribs i and in the centre of each panel is the ornamental figure shown in fig. 3.

The foot of the stove is surrounded by an ornamental scroll moulding and has in the centre a boss e which is enclosed in a panel of the character represented in the drawing.

My claim

The ornamental figures and forms, substantially as shown in and by the accompanying drawing, the whole forming an ornamental design for the plates of the susquehanna cook stove.

For testimony whereof we have signed our names to this specification in the presence of two subscribing witnesses:
